UNITED STATES PATENT OFFICE.

AGOSTINO SANTACROCE, OF CLEVELAND, OHIO.

SHOE-HEEL.

1,351,543.

Specification of Letters Patent. Patented Aug. 31, 1920.

Application filed February 26, 1920. Serial No. 361,605.

To all whom it may concern:

Be it known that I, AGOSTINO SANTACROCE, a subject of the Government of Italy, residing at Cleveland, in the county of Cuyahoga and State of Ohio, have invented certain new and useful Improvements in Shoe-Heels, of which the following is a specification.

This invention relates to heels for shoes and has for its object to provide a novel heel construction of the cushion type, particularly adapted for use on ladies' shoes where high heels are in vogue.

The invention embodies the idea of making a heel of molded rubber, reinforced by a cage of light metal. In one form the metal reinforcement is made of stamped sheet metal. In another form it is made of a casting.

In the accompanying drawings, Figure 1 is a side elevation of the heel cage attached to the shoe; Fig. 2 is a rear elevation of Fig. 1; Fig. 3 is a vertical section of the complete heel; Fig. 4 is a plan of a sheet metal blank from which the heel is made; Fig. 5 is a plan of the top or attaching plate of the cage; Figs. 6, 7 and 8 are details in section on the line 6—6, 7—7, and 8—8 of Fig. 5; Fig. 9 is a detail of a sectional core in the heel; Figs. 10, 11 and 12 are side, rear and front elevations of the cast heel cage; Fig. 13 is a section of the complete heel with the cast cage.

As shown in Fig. 4 the cage comprises a plate 1 which is shaped in plan to correspond to the contour of the heel, and said plate is provided with slots 2, a central opening 3 and a circular aperture 4. Said plate is further provided with extension members 5, 6 and 7, which, when bent at substantially right angles thereto form the sides and back of the heel, these extensions are then shaped to provide the desired form. The extension 7 is provided at one end with a substantially square portion which when bent over at right angles forms the bottom 8 of the cage and slots 9 are provided for a purpose to be hereinafter described.

The extension 6 is further provided with lateral fingers 10 which are bent to enter slots 11 and 12 in the extensions 7 and thereby lock the three extensions together at the bottom. It will be noted that the extensions 5 and 6 are further provided with portions 13 and 14 which are also bent in a manner to lie in a parallel plane to the bottom 8,

and these extensions are further provided with slots 15 for a purpose to be hereinafter described.

The tubular core 20 is adapted to form a vertical support for the heel and is secured in place by being passed through the opening 4 in the top thereof. The bottom of said tube is provided with tongues 21 which pass through the openings 9 and 15 in the parts 8, 13 and 14 after which said tongues are bent in a manner to effectively lock said parts together.

The foregoing assembly is then in condition to be secured to the shoe proper and this is accomplished by providing a plate 25, illustrated in Fig. 5, which is provided with projections 26, 30 and 31, the projections 26 being bent downwardly, and the projections 30 upwardly and at right angles to said plate after which said plate is secured to the shoe by hammering the projections 30 therethrough and clenching the ends as at 32 and is additionally secured by nails passing through the apertures 27. The cage assembly is then secured to the plate 25 by passing the projection 31 through the slot 34, and the projections 26 through the slots 2 aforementioned, it is then further secured by nails 35 passing through the shoe proper. The shoe with the cage assembly is then placed in the proper mold and rubber 50 poured in sufficient quantities to fill the same, and duly vulcanized or hardened, or the heel may be completely formed and attached to the shoe at any time, the heels being made in various sizes or forms to conform to the varying types of shoe styles.

It will be noted that the cage assembly is provided with a plurality of apertures 38 to allow the rubber to enter therein and serve as keys to prevent any movement between the rubber and said cage.

The whole provides a structure of sufficient resiliency to cushion the shocks of walking, but of sufficient stiffness to prevent collapse. The metal parts will yield somewhat, and as shown in Fig. 3, the rubber is preferably extended below the bottom of the cage, as shown at 51, to provide a cushion at the bottom of the heel.

In the form shown in Figs. 10 to 13 the cage 60 consists of a casting or skeleton form with large openings between the ribs or connected parts thereof, to allow the molded rubber to be placed therein. In this form the core may be omitted as unnecessary, since

the casting provides sufficient stiffness for the intended purpose. The top of the casting as shown best in Fig. 12 is provided with slots 2^a corresponding to the slots 2 above described, permitting the use of an attaching plate similar to that shown in Fig. 5, with the tongue 26 being passed through said slots to fasten the castings to the plate which is nailed to the shoe in the same manner as above described.

I claim:

1. A heel comprising a hollow skeleton cage with a top plate, an attaching plate adapted to be secured to the shoe, and attached to said top plate, and a filling of rubber in said cage and projecting below the bottom thereof.
2. A heel comprising a hollow skeleton cage with a slotted top plate, a separate attaching plate adapted to be fastened to the shoe and having tongues engaged in said slots, and a rubber filling in said cage.
3. A heel formed of a sheet metal blank having a top plate, and side and rear extensions bent to form the sides and back of a hollow cage, an attaching plate secured to said top plate, and a rubber filling in the cage.
4. A heel formed of a sheet metal blank having a top plate and side and rear extensions bent to form a hollow cage, said extensions being fastened together at their ends,

at the bottom of the cage, a rubber filling in the cage, and means to attach the top of the cage to a shoe.

5. A heel formed of a sheet metal blank having a top plate and side and rear extensions bent to form a hollow cage, one of said extensions having arms interlocked with the other extensions, and the lower ends of said extensions being fastened together at the bottom of the heel, a rubber filling in the cage, and means to fasten the cage to the shoe.

6. A heel comprising a hollow sheet metal skeleton cage having top and bottom plates, a tubular core extending between said plates, a rubber filling in the cage, and means to attach the cage to a shoe.

7. A heel comprising a hollow sheet metal cage having top and bottom plates, the top plate having an opening and the bottom plate having slots, a tubular core the upper end of which fits in said opening and the lower end of which has tongues engaged in said slots, a rubber filling in the cage, and means to fasten the top plate to a shoe.

In testimony whereof, I do affix my signature in presence of two witnesses.

AGOSTINO SANTACROCE.

Witnesses:

THEODORE BIBISEE,
JOHN A. BOMMARDT.
